UNITED STATES PATENT OFFICE

JOHN W. RACKLYEFT, OF CLEVELAND, OHIO, ASSIGNOR TO THE APEX ELECTRICAL
MANUFACTURING COMPANY, OF CLEVELAND, OHIO, A CORPORATION OF OHIO

IRONING MACHINE

Original application filed February 10, 1927, Serial No. 167,314. Divided and this application filed July 3, 1929. Serial No. 375,670.

This invention relates to ironing machines and has for its object the provision of a simplified and improved design of machine which can readily be folded when not in use to occupy a smaller floor space; which is free from danger of sudden change from position during operation; which can readily be dismembered into separate parts capable of being delivered and installed by one man; while further objects and advantages of the invention will become apparent as the description proceeds. This application is a division of my former application filed February 10, 1927, Serial No. 167,314.

15 In the drawing accompanying and forming a part of this application Fig. 1 is a perspective view of an ironing machine embodying my invention; Fig. 2 is an elevation of the same machine with the frame swinging 20 to vertical position and the bottom of the same being shown; and Fig. 3 is a partial cross sectional view taken through the center of the pivot.

25 My improved ironing machine comprises a rigid frame 1 on which are carried the shoe indicated generally at 2, the roll indicated generally at 3, the motor 4, and the mechanism (housed within the gear box 5) for rotating the roll and for producing and releasing 30 the ironing pressure together with the control devices for such mechanism, here including the buttons 6 and levers 7, 8. The top of the frame 1 is covered with a sheet or tray 9, preferably integral therewith so as to 35 stiffen and strengthen the machine, though obviously capable of being made separate therefrom.

40 For the purpose of mounting the frame 1 so that it may be swung either to horizontal position for use or to vertical position for storage and thereby occupy less floor space, I have provided a single pivot located substantially at the center of gravity of said frame and the mechanism carried thereby. 45 Accordingly the device is substantially balanced at all times, is free from upsetting, and exhibits no lack of stability even though the pivot be not securely clamped. As such pivot I have shown a screw 10 threaded into a lug 50 11 extending upwardly from the rear of the

frame and furnished with a handle 12 by which it may be tightened. The shank 13 of this screw is journaled in the upper end of the pedestal 14 whose lower end is preferably provided with feet 15 and casters 16. 55 The use of the removable pivot screw, coupled with the balancing of the parts, facilitates the manipulation and delivery of the machine by one man. The movement of the parts to upright position when not in use also 60 facilitates the application of a dust jacket or protecting cover. The elimination of balancing springs is an important feature.

It will be understood that any suitable or desired mechanism may be employed for rotating the roll for causing the necessary movements of approach and separation between the roll and shoe, and that many changes may be made in the parts illustrated so that I limit myself only as recited in my 70 annexed claim.

Having thus described my invention what I claim is:

In an ironing machine, in combination, a frame, a shoe carried by said frame, a roll carried by said frame, an electric motor and driving connections carried by said frame for operating said machine, a supporting element for said machine separate from said frame and comprising a vertical pedestal and 75 floor-engaging feet carried thereby, and a removable horizontal pivot screw securing said frame to said pedestal, said screw having a lever whereby said frame can be clamped tightly to said pedestal. 80 85

In testimony whereof I hereunto affix my signature.

JOHN W. RACKLYEFT.
